[57] **CLAIM**

The ornamental design for the combined flat panel display and folding stand with user interface control and stylus therefor, as shown and described.

DESCRIPTION

FIG. 1 is a right front perspective view of a combined flat panel display and folding stand with user interface control and stylus therefor showing our new design; FIG. 2 is a front view of the display, the user interface control and the stylus in a first position, the folding stand being removed.

FIG. 3 is a rear view of the display and the user interface control in a first position;

FIG. 4 is a left side view of the display and the user interface control in a first position;

FIG. 5 is a top view of the display and the user interface control in a first position;

FIG. 6 is a left view of the display and the stand in a folded position;

FIG. 7 is a bottom view of the display and the stand in a folded position;

FIG. 8 is a right side view of the display and the stand in a folded position on a reduced scale;

FIG. 9 is a right side view of the display and the stand in a slanted position;

FIG. 10 is a right side view of the display and the stand in an upright position with a keyboard shown in broken lines for illustrative purposes only and forms no part of the claimed design;

FIG. 11 is a right perspective view of the stand shown separately for clarity of illustration only;

FIG. 12 is a right perspective view of the display, the stand and the user interface control in a second position;

FIG. 13 is a right perspective view of the display, the stand and the interface control in a third position; and,

FIG. 14 is a right perspective view of the display, the stand and the user interface control in a first position, and the stylus inserted in a pocket in the user interface control.

FIG. 1FIG. 2
